UNITED STATES PATENT OFFICE.

GEORGE J. MEYER, OF MILWAUKEE, WISCONSIN.

BOTTLE RINSING AND OUTSIDE-BRUSHING CONVEYER.

1,111,756.

Specification of Letters Patent.

Patented Sept. 29, 1914.

Application filed April 8, 1910. Serial No. 554,290.

To all whom it may concern:

Be it known that I, GEORGE J. MEYER, of Milwaukee, Wisconsin, have invented a Bottle Rinsing and Outside-Brushing Conveyer, 5 of which the following is a specification.

This invention relates to devices for cleansing bottles, and, in particular to that part of a bottle-cleaning plant which rinses the bottles internally and externally after 10 they have been soaked and at the same time brushes them externally; so preparing them for the inside brushing and rinsing.

In general the present apparatus comprises as its principal features a tank containing water, a set of slideways dipping therewith into a conveyor for pushing the bottles along them, a set of rollers which are interposed in and form a part of said slideways, together with means for rotating 20 all of said rollers in the same direction and thereby producing a rotative movement in each bottle about its longitudinal axis, whereby the water which enters the bottle is caused to successively reach 25 every part of its surface; and in addition to this I provide exterior brushes which act in conjunction with said rollers to brush successively each portion of the outside surface of the bottle, thereby cleansing the latter from adhering particles of dirt, paper, 30 or the cleaning-solution which has been used in the previous process.

My invention further consists in the constructions and combinations which will be 35 hereinafter more fully set forth and described in my claims.

The nature of my invention will best be understood by reference to the accompanying drawings which show the most improved form thereof, and herein—

Figure 1 is a side elevation of a complete machine constructed according to my invention; Fig. 2 is a longitudinal section thereof; Fig. 3 is a plan view of the same; Fig. 4 is an end view from the delivery-end of the machine; Figs. 5 and 6 are vertical transverse sections taken on the planes 5 and 6 respectively of Fig. 2; Fig. 7 is a fragmentary transverse section on an enlarged scale showing construction of the pushing-bar; Fig. 8 is a transverse section through the latter on the plane 8 showing a bottle in position therein; Fig. 9 is a plan view of a portion of the same; Fig. 10 is a longitudinal plan-section of the same on the axis of the bottle; Fig. 11 shows the construction

of the gearing for driving the rollers; and Fig. 12 is a fragmentary elevation of the driving gear for the brushes showing the means for adjusting the latter for the different sizes of bottles. 60

In these drawings every reference letter and numeral refers always to the same part.

A shallow tank A is mounted upon legs a' or other suitable means of support, and carries upon each end pulley-brackets d², a³, which support the journals of shafts B, C, each extending across one end of the tank and carrying a pair of sprocket-pulleys b', c', around which pass a pair of chains D 65 which are connected at intervals by the bottle-pushers E secured to links of said chains; the arrangement being such that one lap of the conveyor passes above the tank and through the liquid contained therein, and the other below the tank. The conveyor is driven by a driving-gear c² on the shaft C which is at the delivery-end of the machine, and to prevent the upper lap of the chain being pulled straight and so raised above 70 the level of the water in the tank a pair of curved guides d' are placed immediately over each chain at the infeed-end of the machine and another pair d² at the delivery end. 75

The tank is filled with water by means of a supply-pipe F which enters the tank at f² through a valve f', and at the opposite side is located the drain-pipe G, the upper end of which is provided with a waste-weir g' 80 opening at the water-level, and near the bottom of the tank is a branch or bypass g² which is kept normally closed by a valve g³ and serves to drain the tank when it is desired to remove the water therefrom for the purpose of cleaning or repairs. This is also assisted by hand-holes a⁴ in each side of the tank, which are closed by covers a⁵; but the latter are not essential to my invention. 85

Across the open top of the tank is disposed a platform having slideways over which the bottles are pushed, and said platform is made in three parts, to wit: beginning at the infeed-end, a series of parallel semi-cylindrical bars H, which are longitudinally concave as shown in Fig. 2, the upper end being pitched at a downward angle and sloping into the tank, while the lower end is pitched slightly upward and is below the water level a⁶ a distance sufficient to 90 half-submerge the bottle, which rests longitudinally between two adjacent bars and 100

105 110

is delivered thereto heel-foremost. The second or middle part of the aforesaid platform comprises a series of rollers I which are continuous and codiametral with the bars H and are provided at their ends with 5 gudgeons i' journaled in bearings J, which are carried upon a pair of transverse beams j' supported by the ends of the tank or otherwise. These rollers are kept in continuous 10 rotation all in the same direction by a driving-shaft K carrying a set of spiral-gears k' keyed thereon, each meshing with a corresponding spiral-gear k² on the shaft or gudgeon i' at the head-end of each roller, 15 which latter is keyed to said shaft or gudgeon by a transverse pin i² or like device. The spiral-gears k' may be secured against endwise shifting upon the shaft K by providing their keys k³ with projecting snugs k⁴ at 20 the thrust-side of the gear. The shaft K is supported at its ends and intermediately by journals k⁵, k⁶, k⁷ through one of which the shaft passes and extends beyond it and carries a sprocket-pinion M, which is driven by 25 a chain N passing over a sprocket-wheel O on the shaft B.

The third section of the aforementioned platform comprises a second series of semi-cylindrical bars P which are codiametral 30 and continuous with the several rollers I and at the ends of the latter, whereby the bottles readily pass from the interspaces between the rollers to those between the bars P as they are pushed thereupon by the continuous 35 movement of the pusher-bars E. These bars P are sloped upwardly so as to convey the bottles out of the water in the tank and at the same time tilt them neck-downward so that all the water that happens to be 40 therein will run out. Above the end of the end or delivery section of the platform is mounted a tray Q upon brackets Q' for receiving the bottles as fast as they are removed from the platform.

45 The construction of the pusher-bar E is illustrated in detail in Figs. 7 to 10 inclusive. It comprises a transverse angle-bar e' which acts as a base and support and is secured to the links of the chain D, and a series of 50 double socket-castings e², each socket of which is scoop-shaped and provided with a downwardly and forwardly projecting nose e⁸ which fills the spandrel between two adjacent rollers or bars of the platform. These 55 socket castings e² are secured to the upright flange of the angle-bar e' by bolts e⁴ passing through holes e⁵ in the castings; each bolt being located at the center of a circular recess e⁹ and having a rounded projecting head e⁸. Now when the bottles are delivered, 60 either by hand or a conveyer, onto the inclined bars H, they slide down these bars ahead of the pusher and come to rest on the rollers I, the necks of the bottle in most of 65 the usual shapes being sufficient to over-

balance the body so that the neck inclines downwardly. While in this position the bottles become partially filled with water, and subsequently the next following pusher E reaches them and the projecting nose e⁸ thereof raises up the mouth of each bottle and places it in the center of the recess e⁹, so that the spherical head e⁸ of the bolt e⁴ enters the mouth thereof. Now said recess e⁹ and head e⁸ are preferably so placed as to 70 raise the mouth of the bottle sufficiently to tilt the bottle upward until it rests upon its bottom edge only, in addition to the support provided by the head e⁸, which thus acts as a pivot upon which the bottle turns and 75 keeps it in alinement with the rollers and direction of movement.

To prevent bottles from becoming broken by striking the rear edge of the angle-bar e' when they slide down the inclines H, a 80 wooden fender-strip e⁶ is secured to the latter by bolts e⁷, projecting slightly beyond the edge of the angle-bar.

When the bottles after sliding down the inclined bars H reach the rollers I, they are 90 set in rapid rotation about their longitudinal axes, so that the water rinses them inside and out and loosens any of the solid particles which may remain inside of the bottles. They are then taken up by the 95 next following pusher E in the manner aforesaid and carried onto the bars P, in which position they are tilted neck downward so that all the water and solid particles which have been loosened up run out, and as the 100 bottles reach the delivery end of the machine they are lifted out by the operatives heel-first and any remaining water thus drained from them, and thence placed upon a tray Q, where they are further drained 105 and from which they are removed to the inside brushing-machine.

Although the rolling movement of the bottles itself serves to rinse the outside to a certain extent, I prefer to provide additional 110 means for outside cleaning in the form of a pair of rotary brushes S, T, which are mounted upon shafts s', t', journaled in vertically sliding bearing-blocks s², t², which slide in slots u', u², in a pair of end-frames 115 U mounted on the sides of the tank. Said bearing-blocks s², t², are supported and adjusted vertically by means of screw-stems s³, t³, secured thereto and provided with hand nuts s⁴, t⁴, by revolving which the 120 bearing-blocks and hence the shafts are raised or lowered in the manner shown in Fig. 12, thus permitting the brushes to be adjusted to different sizes of bottles. Said brushes are rotated by a gearing comprising 125 sprocket-wheels s⁵, t⁵, on their respective shafts s', t', a sprocket-wheel V on the shaft K, and a chain v' passing over all three sprocket-wheels. In order to provide for the continuous and equal tension of the chain 130

v' under different adjustments of the brushes I arrange upon one lap of the chain, lying between the sprocket-wheels V and s^5 , an idle sprocket-wheel W, which is pivoted 5 upon a pin w' carried by a lever w^2 pivoted at w^3 upon the framework or side of the tank, said lever w^2 having an angular-extension w^4 carrying a weight w^5 so placed as to act to rotate the lever w^2 in a direction 10 toward the chain, thus keeping the sprocket-wheel W continuously pressed thereagainst with an even pressure, independently of the positions of the brushes, as indicated by the full and dotted-line positions of said lever 15 and sprocket-wheel. The weight w^5 may be shifted or increased or diminished according to the tension desired.

As the bottles are carried along the platform and partly immersed in the water in 20 the tank they are brushed over longitudinally by the two brushes at the same time that they are being rotated by the rollers I so that every part of the lettering or other irregular surfaces of the outer surface is 25 brushed. Further, in order to facilitate the washing-off of any adherent particles as well as to constantly renew the water in the tank, I provide a water-supply in the form of a pair of spray-pipes X which extend 30 parallel with the brushes and immediately over them and are perforated by small holes and connected through branch-pipes x' , x^2 , and valves x^3 to the watermain F; the excess of water drains out through the waste 35 weir y' , thus keeping the level constant. To prevent undue scattering of the water a hood or cover Y is placed over the brushes, secured to the end-plates or frames U and having in the middle a door y' hinged at 40 y^2 to one of two angle-plates y^3 on the edge of the fixed portion of the hood, said door being provided with handles y^4 whereby it can be opened and the interior inspected. The bottle conveyer moves in the direction 45 of the arrow seen in Fig. 1.

Various changes and modifications in the constructions as herein shown may be made without departing from the spirit of my invention, and I wish it understood therefore that the latter is not otherwise limited than by the proper scope of my claims.

Having thus described my invention, what I claim as new and desire to secure by Letters Patent, is:

55 1. The combination of a runway for bottles, means for rotating bottles on said runway by frictional contact, and a movable center-support for the mouth-end of said bottles consisting of a scoop-shaped block 60 adapted to receive and center the mouth of a bottle and act as a pivot about which it turns.

2. The combination of a runway for bottles, means for rotating bottles on said runway by frictional contact, and a movable

center-support for the mouth-end of said bottles consisting of a scoop-shaped block adapted to receive and center the mouth of a bottle and act as a pivot about which it turns, said scoop-shaped block being open 70 at the top, in conjunction with means for advancing said block parallel to said runway and frictional cleaning-means located above said runway and adapted to contact with the surface of the bottle as it passes 75 along said runway.

3. The combination of a plurality of parallel cylindrical rollers in the spandrels between which bottles are adapted to rest, having their axes parallel thereto, means 80 for rotating said rollers in the same direction so as frictionally to give a rotative movement to said bottles, a member carrying a plurality of scoop-shaped blocks projecting into said spandrels, and each adapted 85 to pick up the mouth of a bottle presented to it and support it above the level which it would otherwise occupy whereby its upper surface is approximately on a level with that of the body of the bottle, means 90 for advancing said member so as to move said bottles longitudinally along said rollers in advance of said member, and means immediately over said bottles adapted to brush them as they move along said rollers. 95

4. The combination of a plurality of parallel cylindrical rollers in the spandrels between which bottles are adapted to rest having their axes parallel thereto, means for rotating said rollers in the same direction 100 so as frictionally to give a rotative movement to said bottles, a member carrying a plurality of scoop-shaped blocks projecting into said spandrels and each adapted to pick up the mouth of a bottle presented to it and 105 support it above the level which it would otherwise occupy whereby its upper surface is approximately on a level with that of the body of the bottle, means for advancing said member so as to move said bottles longitudinally along said rollers in advance of said member, and means for supporting a liquid around said bottles when in said runway, in such position that the surface of said liquid passes through said bottles. 110

5. The combination of a runway for bottles, means for rotating bottles on said runway by frictional contact, and a movable center-support for the mouth-end of said bottles consisting of a scoop-shaped block 120 adapted to receive and center the mouth of a bottle, said block having a circular recess into which the mouth of the bottle fits and a projection in the center of said recess adapted to enter the mouth of the bottle and 125 form a pivotal center therefor.

6. The combination of a runway for bottles, means for rotating bottles on said runway by frictional contact, a movable center-support for the mouth-end of said bottles, 130

consisting of a scoop-shaped block adapted to receive and center the mouth of a bottle, said block having a circular recess into which the mouth of the bottle fits, a member to which said block is secured, and a bolt securing said block to said member, said bolt having a head which projects concentrically within said recess and is adapted to enter the mouth of the bottle and form

a pivotal center for the rotation of the bottle.

In witness whereof I have hereunto set my hand this 25th day of March, 1910.

GEO. J. MEYER.

Witnesses:

JAS. L. WARNER,
GEORGE W. COLLES.
